UNITED STATES PATENT OFFICE

ARTHUR LEV, OF BRONX, NEW YORK

SAFETY RING GUARD

Application filed June 13, 1931. Serial No. 544,226.

This invention relates to certain new and useful improvements in safety ring guard.

The primary object of the invention is to provide a guard attachment for finger rings in the form of a strip of material fashioned at its ends for engagement with portions of a ring band with the strip positioned inwardly of the band for reducing the diameter of the latter to prevent the escape or loss of the ring from a finger.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a developed perspective view of a safety ring guard constructed in accordance with the present invention;

Figure 2 is a side elevational view of a ring with the guard in position thereon;

Figure 3 is a cross-sectional view taken on line 3—3 of Figure 2;

Figure 4 is a developed perspective view of another form of ring guard;

Figure 5 is a side elevational view of a ring with the ring guard shown in Figure 4, in position thereon;

Figure 6 is a cross-sectional view taken on line 6—6 of Figure 5;

Figure 7 is a cross-sectional view taken on line 7—7 of Figure 5;

Figure 8 is a developed perspective view of another form of ring guard;

Figure 9 is a side elevational view of a ring with the guard shown in Figure 8 in position thereon;

Figure 10 is a cross-sectional view taken on line 10—10 of Figure 9; and

Figure 11 is a cross-sectional view taken on line 11—11 of Figure 9.

In the form of invention illustrated in Figures 1 to 3, the ring guard comprises an elongated metallic strip 15 having a cut-away portion or notch 16 in opposite side edges thereof as shown in Figure 1 adjacent opposite ends and each opposite edge of the

strip 15 in line with the notch 16 carries an outwardly or laterally directed tongue 17.

In mounting the guard upon the ring band R shown in Figure 2, the strip 15 of the guard is bent into arcuate form for engagement with the inner side of the ring band, the tongue 17 being bent in opposite directions around the ring band with the terminal ends of the tongue entering the associated notches 16 at the inner side of the ring band. By extending the outer terminal end of the finger 17 into the associated notch 16, the finger is retained in its proper position against lateral displacement or distortion by the side walls of the notch so that when the guard is mounted on a finger ring and the ring is worn on a finger, escape of the guard is prevented, as the inner face of the guard including opposite ends thereof and the terminal ends of the fingers 17 lie in contact with the finger of the wearer. The terminal end of the finger 17 lies within the plane of the strip 15 as shown in Figure 3 so that no projections are present which would injure the finger of the wearer, or catch into wearing apparel or the like.

In the form of invention shown in Figures 4 to 7, the guard strip 15a has an outwardly or laterally directed finger 18 projecting from each side edge thereof adjacent opposite ends and the adjacent edge portions of the strip opposite the tongues 18 carry a pair of outwardly or laterally directed lugs 19 with a lug aligned with each side edge of the associated tongue 18.

The guard shown in Figure 4 is illustrated in Figures 5 to 7 as operatively engaged with the ring band R, the strip 15a being bent into arcuate form as illustrated, while the tongues 18 are bent around the ring band in opposite directions, the lugs 19 having been first bent into engagement with a side face of the strip 15a while the terminal ends of the tongues 18 are positioned between the lugs 19 thereby raising the ends of the strip or guard from the ring band.

Another form of ring guard is shown in Figures 8 to 11, the strip 15b having a cut out portion or notch 16a formed in opposite side edges thereof adjacent opposite ends and an

outwardly or laterally directed tongue 17a carried by each edge of the strip 15b at the sides thereof opposite the notches 16a and adjacent the inner edges of the notches. The 5 guard strip 15b is associated with the ring band R, illustrated in Figures 9 to 11 by first bending the sections 15c of the strip that lie outwardly of the tongues 17a in an inward direction to overlie one side of the strip 15b 10 with the notch 16a aligned with the tongue 17a. The tongues 17a are then bent around the ring band R with the terminal ends of the tongues 17a extended into the notches 16a.

It will be observed that the strips 15, 15a 15 and 15b are in no way weakened, as the tongues 17, 17a and 18 as well as the lugs 19 are additional elements and are not struck-out from the different strips. In all forms 20 of the invention, the guard strips are present- ed for engagement with the finger of the wearer and all prongs, tongues and lugs are interposed between the strips and ring band. The tongues being bent into positions be- 25 tween the associated locking lugs and recess walls, and disposed between the strips and ring band, displacement thereof is eliminated.

While there are herein shown and de- 30 scribed the preferred embodiments of the present invention, it is nevertheless to be understood that minor changes may be made therein without departing from the spirit and scope of the invention as claimed.

I claim:

35 1. A finger ring guard comprising a me- tallic strip, a laterally directed tongue at each end of the strip for securing the latter to a finger ring, and means engageable with opposite sides of the free end of each tongue 40 to prevent movement of the tongue in a di- rection lengthwise of the strip, the side edges of the tongue ends lying within the plane of said means and prevented from contacting the finger of the wearer and said means being located at the inner side of the finger ring.

45 2. A finger ring guard comprising a me- tallic strip, a laterally directed tongue at each end of the strip for securing the latter to a finger ring, and means engageable with op- 50 posite sides of the free end of each tongue to prevent movement of the tongue in a di- rection lengthwise of the strip comprising means on the strip to be engaged by the tongue, the side edges of the tongue ends lying within the 55 plane of said means and prevented from con- tacting the finger of the wearer and said means being located at the inner side of the finger ring.

60 3. A finger ring guard comprising a me- tallic strip, a laterally directed tongue at each end of the strip for securing the latter to a finger ring, and means engageable with op- 65 posite sides of the free end of each tongue to prevent movement of the tongue in a di- rection lengthwise of the strip comprising means

on the strip to be engaged by the outer terminal end of the tongue, the side edges of the tongue ends lying within the plane of said means and prevented from contacting the finger of the wearer and said means being lo- 70 cated at the inner side of the finger ring.

4. A finger ring guard comprising a me- tallic strip, a laterally directed tongue at each end of the strip for securing the latter to a finger ring, said strip having a notch in each edge thereof opposite the tongue for recep- 75 tion of the terminal end of the tongue with the walls of the notch at opposite sides of the tongue end to prevent movement of the tongue end in a direction lengthwise to the strip, the side edges of the tongue ends lying within the plane of the strip and prevented from contacting the finger of the wearer.

5. A finger ring guard comprising a me- tallic strip, a laterally directed tongue at each end of the strip for securing the latter to a finger ring, a pair of lugs projecting from each edge of the strip opposite the tongue with one of the lugs at each side edge of the associated tongue, the lugs being engaged 80 with a side face of the strip and the tongue end disposed between the lugs.

6. A finger ring guard comprising a me- tallic strip, a laterally directed tongue at each end of the strip for securing the latter to a finger ring, said strip having a notch in each edge thereof opposite the tongue and disposed outwardly of the tongue, the notched ends of the strip occupying an overlying position rel- 85 ative to the strips when in service and the end 90 of the tongue being extended into the associated end notch.

In testimony whereof I affix my signature.
ARTHUR LEV.
